(57) CLAIM

The ornamental design for a case for skin treatment apparatus, as shown and described.

DESCRIPTION

1. Case for skin treatment apparatus

1.1 : Perspective

1.2 : Front

1.3 : Back

1.4 : Left

1.5 : Right

1.6 : Top

1.7 : Bottom

1.8 : Perspective, shown in an open condition of use.

The broken lines in Figure 1.8 disclose portions of a skin treatment apparatus that form no part of the claimed design.
